ATTORNEY

UNITED STATES PATENT OFFICE.

BERNHARDT BECK, OF CUT BANK, MONTANA.

ELECTRIC BURGLAR-ALARM.

1,285,596.

Specification of Letters Patent. Patented Nov. 26, 1918.

Application filed March 9, 1918. Serial No. 221,379.

To all whom it may concern:

Be it known that I, BERNHARDT BECK, a subject of the Emperor of Germany, resident of Cut Bank, county of Teton, and 5 State of Montana, have invented certain new and useful Improvements in Electric Burglar-Alarms, of which the following is a specification.

This invention relates to improvements 10 in burglar alarms and particularly to types adapted to be engaged with the doors of a building in which it is desirable to give an audible signal whenever the door is unlocked.

15 The principal object of the invention is to provide an apparatus which will cause a signal to be given whenever a key is inserted in the door lock.

A further object is to provide such device 20 which may be permanently engaged with one side of the door lock, the apparatus being in sections one of which is readily removable so as to present no disfigurement or objectionable appearance.

25 These and other like objects are attained by the novel construction and combination of parts hereinafter described and shown in the accompanying drawing, forming a material part of this disclosure, and in 30 which:—

Figure 1 is a fragmental edge view of a conventional form of door, containing an ordinary lock and operating knobs and indicating the application of the invention.

35 Fig. 2 is a vertical sectional view taken through the center of the key-hole and indicating the operation of the device.

Fig. 3 is a fragmental side elevational view of the same, and

40 Fig. 4 is a vertical sectional view taken on line 4—4 of Fig. 2.

Throughout the several figures the numeral 10 designates a door of conventional type, containing a lock-casing 11, through 45 which extends a lock bolt 12, engageable with a keeper formed in the frame of the door (not shown), and a latch 13, operated by the knobs 14, all of the foregoing parts being of the usual type of construction.

50 Secured to the inner side of the door 10, so as to cover one of the key-openings 16, is a flat plate 17, the same having angularly disposed elements 18, upon opposite ends, terminating in flanges 19, secured perma-

nently by screws 20, to the side of the door, 55 and containing an elongated vertical slot 22, formed centrally through the plate 17, through which may be passed a rectangular plate 23, secured to the lower end of a tubular screw 25, passing freely through the 60 slot 22, and a wooden block 26, which has a counterbored opening 27, in its outer surface, containing the lower end of a helically coiled compression spring 28, the outer end of which abuts against a washer 29, and is 65 compressed by operating a knurled nut 30, the purpose of the same being to clamp the plate 23, when arranged transversely across the slot 22, against the inner side of the plate 17, so as to hold the block 26 in engagement. 70

Passing centrally through the bore of the tubular screw 25, is a rod 32, adapted to enter the key-hole 16, and register with the stem of an entered key 35, there being secured to the rod 32, a fixed collar 33, which, when the rod is extended as far outward as is possible, will make contact with the plate 23. 75

The outer extending end of the rod 32, is screw threaded and has secured to it a conical metallic sleeve 36, adjoining which is a thimble 37, having secured to its outer end a knob 38, made of non-conducting material, and having an inner extending stem 39 of cylindrical shape adapted to engage 85 with the curved ends 40, of a pair of opposed flat springs 42, secured to the wooden insulating block 26, by binding screws 43, which engage wires 44 and 45, respectively, which lead from a source of electricity, as an 90 ordinary primary cell battery (not shown) and in circuit with which is an electric bell. 95

In operation, the plate 17, is permanently secured to the inner side of the door, the slot 22 in the plate alining with the key hole, 95 so as to permit the lock to be operated in the ordinary manner.

When it is desired to attach the alarm, the block 26, is secured in position by pressing the knob 38 inward, so as to allow the 100 plate 23 to enter and pass through the slot 22, whereupon releasing the knob, the spring clamps the block firmly in engagement with the outer surface of the plate 17. The knob 38 is pressed in to its full extent, causing the 105 springs 42, to slide over the cone 36, and over the rounded edges of the intermediate thimble 37, resting upon the cylindrical

- surface 39 of the knob 38, holding the rod 32, in an inward position, as best shown in Fig. 1, so that when contact is made at the extreme end of the rod 32 by the entrance of the key 35, the rod 32 will be pushed out, carrying the knob with it and allowing the springs 42 to make contact with the cone 36, which completes the circuit, causing an alarm by reason of the electric bell, giving audible notification that a key has been entered in the lock. Obviously, when the springs 42 are held apart by the knob stem 39, the circuit is broken and no current is conveyed to the alarm.
- 15 From the foregoing it will be seen that when the attachment is not in use it can be readily removed by pressing the knob 38 toward the door, rotating the block and removing the same together with its attachments.
- 20 Having thus described my invention what

I claim as new and desire to secure by Letters Patent, is:—

In a burglar alarm, in combination, a door, a lock engaged therewith, a rigid plate supported by said door, a block engageable therewith, means for clamping said block to said plate, a tubular screw slidable in said block, a spring operating to move said screw within said block, means for adjusting the tension of said spring, a rod slidable engaged in said tubular screw, a pair of contact arms arranged upon opposite sides of said block, an insulated knob formed at the extreme end of said rod, and a conical 35 engaging element adjacent to said knob, whereby when said rod is pressed outwardly said contact arms are placed in circuit.

In testimony whereof I have affixed my signature.

BERNHARDT BECK.
